UNITED STATES PATENT OFFICE.

FRANK E. WILLIAMS, OF ST. LOUIS, MISSOURI.

APPARATUS FOR MOLDING.

Application filed April 26, 1924. Serial No. 709,295.

To all whom it may concern:

Be it known that FRANK E. WILLIAMS, a citizen of the United States, residing at 3817 Easton Avenue, in the city of St. Louis and State of Missouri, has invented certain new and useful Improvements in Apparatus for Molding, of which the following is a specification.

This invention has to do with the art of molding; and relates more specifically to an apparatus for expediting the solidification of castings from their fluid state, and, also, for producing hollow castings in a novel manner by reason of such rapid solidification. The invention is especially applicable to the production of castings from paraffin or other material having similar properties.

In the accompanying drawings forming part of this specification, in which like numbers of reference denote like parts wherever they occur,

Figure 1 is a perspective view of the preferred form of this apparatus;

Figure 2 is a transverse vertical sectional view through the mold of this preferred form;

Figure 3 is a transverse view of a modified form of mold;

Figure 4 is a vertical longitudinal central sectional view through the mold of Figure 1;

Figure 5 is a perspective view of another type of mold embodying the features of this invention, a vertical longitudinal central section being shown through the same;

Figure 6 is a plan view of still another form of mold, parts being shown in section on the line 6—6 of Figure 8;

Figure 7 is an elevation of the same, partly in section on the irregular line 7—7 of Figure 6;

Figure 8 is a transverse sectional view on the line 8—8 of Figure 6; and

Figure 9 is a similar view, but with the mold shown in open position.

Referring to the form of this invention depicted in Figures 1, 2, and 4, a supporting frame comprises bottom member or floor 1, having a pit or recess 2 at its rear end, and uprights 3 and 4 at either side. L-shaped flanges 5 and 6 project outwardly from the respective uprights 3 and 4 near their tops 7, so as to form channels 8, extending from the front to the rear of the frame.

Bearing boxes 9 rest slidably in the chan-

nels 8, and have journaled therein the pipes or hollow shafts 10, the inner ends of which screw into cross-fittings 11, the inner ends of which cross-fittings 11 have screwed thereinto the nipples 12, the inner ends of which nipples 12 are screwed into the respective ends of the middle, hollow mold member or block 13.

Molding block 13 has secured to the bottom thereof, and near each of its ends, by means of screws 14, the transverse beams 15, terminating at suitable distances beyond the sides 16 of the block 13 in upright brackets 17, which support rods 18 passing through holes 19 in the said brackets, and which rods are threaded at their ends for the reception of nuts 20, which nuts are screwed home against the outer faces 21 of the brackets 17, thus securing rods 18 in place. Rods 18 pass through the middle molding block 13, and the outer hollow molding blocks 22, arranged one on each side of middle block 13, the said rods fitting slidably in the holes 23 of the said blocks. Outer blocks 22 are thus slidable toward and away from the middle block 13, the said blocks co-operating to form the parts of a mold, which is open when the blocks are separated, and closed when they are together, the innersides 24 of the outer blocks 22 co-operating with the respective outer sides 25 of the middle block 13 to form the parting faces of the mold, the cavities 26, having the configuration of the articles to be molded being partly in the sides 24 of blocks 22 and partly in the sides 25 of block 13. Blocks 13 and 22 are preferably formed of aluminum alloy, or some other good heat-conducting materials.

Nipples 27 are screwed into the ends of the blocks 22, and L-fittings 28 are screwed into the front and rear openings of cross-fittings 11, the said nipples and L-fittings being connected by hoses or flexible tubes 29.

The mold is retained in closed position, when desired, by a latch 30, having a loop 31 at one end which passes around one of the nipples 27, and a resilient hook 32 at the other end which engages the other nipple 27 on the opposite outer block 22.

When the mold occupies the position at the forward end of the supporting frame, as shown in Figure 1, it cannot be inverted or tilted, by reason of the stopping flanges 33 interfering with or blocking the swing of the L-fittings 28 and hoses 29. The stopping

flanges 33 extend only along the forward portions of the uprights 3 and 4, so that when the mold has been nearly moved toward the rear of the frame, flange 33, by reason of its termination at 34 no longer interferes with or obstructs the swing of the L-fittings 28 and hoses 29. If, however, the mold be moved still further back, nipple 27 engages slot 35, in bracket 36, preferably 10 cast integral with upright 3, and so secures the mold against turning.

The pit or container 2 contains molten paraffin, which may be kept heated by any suitable means, as, for instance, by being 15 placed over a gas burner.

Connections 37, preferably flexible, lead from and to a supply of refrigerant, such as brine, which may be kept circulating through the system, including the cavities 26 in the 20 blocks 13 and 22 and the several pipe and hose connections hereinbefore described, by any suitable means, such as a pump.

A frame 39, in the present instance of rectangular shape, is placed on top of the 25 mold (which is in the position indicated in Figure 1) preparatory to pouring the paraffin. A predetermined quantity of molten paraffin is then dished out of the pit 2 in a suitable receptacle in the hands of the operator, and poured into the space enclosed by the frame 39, from whence it flows into the 30 cavities 26. The metal walls of the cavities 26, being cooled by the circulating refrigerant, congeal that portion of the paraffin in immediate contact therewith, forming a hollow shell of solid paraffin containing a core of warmer and still molten paraffin. Before the molten pour has had time to congeal 35 the frame 39 is removed and the mold is pushed almost to the rear of the supporting frame, where it is free to turn, and is then inverted the molten paraffin flowing out and returning into the reservoir or pit 2 to the source of molten paraffin supply. The mold 40 is then again turned top-side up, and pushed further back so that the nipple 27 engages slot 35, thereby preventing accidental turning of the mold. The solidified gate or surplus of paraffin remaining on top of the mold 45 is severed from the individual castings by passing a knife along the top of the mold, and the severed portion is returned to the pit 2. The mold is now moved retracted slightly to turning position, again inverted, 50 and then further retracted to its forward position, whereupon latch 30 is disengaged, and the blocks 22 moved away from the block 13, the castings 40 thereupon being released and falling on the floor 1 or on any 55 other suitable receiver placed thereon. Blocks 22 are now again returned to their normal position against the block 13, the latch 30 again swung to locking position, the mold moved back to turning position, 60 turned top-side up, and then finally moved 65

forward to its original position as shown in Figure 1, when the foregoing cycle of operations may be repeated to make another batch of castings.

A non-refrigerated mold would soon become too warm by continuous use, so that the time required for the castings to congeal would be unduly prolonged. Besides expediting the production of castings, by maintaining the mold at a temperature requisite therefor, by means of refrigeration, the mold of the present invention enables the production of hollow castings without the use of a core, because of the resultant congelation of the shell of the casting in advance of its internal portion. Moreover, the continuous production of castings is further materially facilitated by reason of the pivoting of the mold in the blocks 9, and the reciprocation of the said blocks in the channels 85 8, as well as by the ease with which the mold may be repeatedly opened and closed by reason of the sliding of its outer blocks 22 on the guide rods 18, in connection with the use of the latch 30. 90

It is not necessary that the cavities 26 be directly in the blocks 13 and 22, but the cavities 26 may be formed in matrix plates 41 attached to the side or sides, as the case may be, of the blocks 13 and 22, by screws 42, as shown in Figure 3. 95

Figure 5 shows an alternative form of open mold, in which the matrix plates 43 are secured to the top and bottom faces respectively of the mold 44, by means of the 100 screws 45. In molds of this type, it is desirable to cool both top and bottom simultaneously and uniformly. In practice, however, that portion of the mold chamber or cavity 46 above the nipples 12 forms an air 105 pocket, which prevents the refrigerant from reaching and cooling directly whichever side of the mold, for the time being, is on top. The result of this condition is that the oppositely disposed matrices are alternately 110 heated and cooled with every inversion or half turn of the mold. To compel the current of brine to circulate through the mold alternately from top to bottom in a zig-zag 115 course, a series of transverse baffle plates 47 are preferably provided therefor. The baffle plates 47 project alternately from the top and bottom sides of the cavity 46 to, preferably, about half-way across the cavity 46. To 120 vent the air from the chamber 46 to prevent the formation of an air pocket, the valve 48 is provided at one end of the mold, being threaded into opening 49, leading into the chamber 46 adjacent its upper wall. Ports 50 in the top of the baffle plates 47 similarly 125 vent the air between the plates. These improvements for uniformly cooling both sides of the mold are not necessarily restricted in their use to the form of mold depicted in Figure 5, but may be adapted to various 130 135

kinds of molds, including the form shown in Figures 1 to 4 inclusive.

Figures 6, 7, 8, and 9 depict a form of mold especially suitable for casting bottles and similarly shaped objects. The mold comprises 2 sections or blocks 51 and 52, which are hinged together at 53 to permit of closing them upon one another. The cavity or passage for the circulating refrigerant 10 of block 51 divided into 3 branches 54, 55, and 56, which contain the baffle plates 57, having air vent ports 58. To vent the air from the several cavities through the end of the mold, a threaded opening 59 having a removable screw plug 60, in lieu of a valve 48 as depicted in Figure 5, may be used. A latch 61, pivoted on a pin 62 on the side of the mold opposite that of the hinges 53, has a resilient hook 63 which engages a pin 20 64, so that the two parts of the mold may thereby be locked together. Part 51 contains cavities 65 for casting bottles, and part 52 contains cavities 66 for casting the lids or covers for the bottles. Cavities 65 are in 25 staggered relation to cavities 66, so that each part forms a cover for the cavities of the other part. Part 52 is cooled by contact with part 51. The castings 67 and 68 may be removed by opening the mold, as shown 30 in Figure 9, and applying to the face of the mold a cup 69, which receives compressed air through a tube 70 leading thereto. Or the cup 69 may be formed of material such 35 as rubber, and a solid handle thereon in lieu of a tube may be operated manually to compress the air already in the cup, and thereby force out the castings.

The baffle plates used in the several molds not only force the circulating brine to pass from the bottom to the top and vice versa, but they also present an additional metal surface to impart heat to the refrigerant, and thereby increase the available cooling 45 surface.

Figure 10 depicts a modification of the form of mold shown in Figures 6 to 9 inclusive. Instead of the cover 71 being hinged, it is slidable in a groove or channel 72 formed at either end in flanges 73 extending from the top of the mold 74. When casting, the cavities 75 are closed by sliding the cover 71 to bring the openings 76 in the cover 71 out of registration with the cavities 75, but when the castings are to be removed, the cover is moved to bring the openings 76 into registration with cavities 75 thereby allowing the castings to be discharged through the openings 76.

Having thus described this invention, I hereby reserve the benefit of all changes in form, arrangement, order, or use of parts, as it is evident that many minor changes may be made therein without departing from the spirit of this invention or the scope of the following claims.

I claim:

1. In a molding apparatus, the combination of a support, a mold movably mounted thereon, a container arranged below the mold to receive surplus molding material discharged therefrom, when the mold is in one position and a floor arranged below the mold to receive the castings discharged therefrom when the mold is in another position.

2. In a molding apparatus, the combination of a support, a member mounted thereon for back and forth movement, a mold pivoted to the said member, means to lock said mold against turning when said member is in its extreme forward position, means to lock said mold against turning when said member is in its extreme rear position, a floor arranged to be under the said mold, when said member is in its forward position, and a container arranged to be under the said mold when said member is in its rear position.

3. In a molding apparatus, the combination of supporting means; a mold chargeable in one position and dischargeable when inverted therefrom, and borne by the supporting means rotatably so that it may be turned from one position to the other, and shiftably so that it may be reciprocated from a charging location at one end of its stroke to a discharging location at the other end of its stroke; and means constraining the mold from turning from its appropriate position at the end of a stroke.

4. In a molding apparatus, the combination of supporting means; a mold chargeable in one position and dischargeable in another, and borne by the supporting means rotatably so that it may be turned from one position to the other, and shiftably so that it may be reciprocated from a charging location at one end of its stroke to a discharging location at the other end of its stroke; means constraining the mold from turning from its charging position when it is at the charging location, and means constraining the mold from turning from its discharging position when it is at the discharging location.

5. In a molding apparatus, the combination of supporting means, a mold that comprises separable co-operating matrices and is borne by the support rotatably for inversion and shiftably so that it may be reciprocated from a charging location at one end of its stroke to a discharging location at the other end of its stroke, means whereby the separable matrices may be locked together during a stroke, and means constraining the mold against turning from its appropriate position at the end of a stroke.

6. In a molding apparatus, the combination of a supporting track, a member mounted to reciprocate thereon, a mold pivoted to the said member, and means for

automatically locking said mold against turning only when said member arrives at the end of a stroke with the mold in a predetermined position.

5. 7. In a molding apparatus, the combination of a pair of oppositely disposed standards, a pair of blocks each adapted for a reciprocating movement on a respective standard, a mold intermediately the said blocks and pivoted thereto, and means to lock said mold automatically against turning when said blocks arrive at the end of their stroke with the mold in an appropriate position.

15. 8. In a molding apparatus, the combination of a support, a member mounted to reciprocate thereon, a mold pivoted to the said members, means for automatically locking said mold against turning when said member arrives at the end of a stroke with the mold in a predetermined position, means arranged to be under the mold at one end of the said stroke to receive surplus molding material discharged from the mold thereat, 25 and means arranged to be under the mold at the other end of the stroke to receive the castings discharged from the mold thereat.

30. 9. In a molding apparatus, the combination of a base having upstanding guiding supports at each end, a pair of blocks tracking thereon and guided thereby in a back and forth movement, a mold intermediately the said blocks and pivoted thereto, and a projection on a said support arranged to be engaged by the mold to prevent the latter from turning when it arrives at the end of a stroke in a predetermined position.

35. 10. In a molding apparatus, the combi-

nation of a base having upstanding guiding supports disposed one at each end, a pair of blocks thereon guided thereby in a back and forth movement, a mold intermediately the said blocks and pivoted thereto and provided with front and rear end projections, means borne by the front portion of one of said supports to engage the front end projection of the mold to prevent the mold from tilting from its proper position thereat when it arrives at the forward end of its stroke, and means borne by the rear portion of one of said supports to engage the rear end projection of the mold to prevent the mold from tilting from its proper position thereat when it arrives at the rear end of its stroke.

40. 11. In a molding apparatus, the combination of a base having a pit-like depression at its rear side for receiving molding material and having uprights disposed one at each end, and a mold supported on the uprights and adapted to be moved back and forth thereon so as to bring the mold into and out of a position directly over the pit.

45. 12. In a molding apparatus, the combination of a pair of oppositely disposed supports, a row of separable co-operating molding blocks intermediately the supports and having aligned bearings, the nearest-to-the-middle block having projections one on each end and borne by a respective support, a guide rod disposed along the row of blocks and passing through the bearing of each block and a supporting bracket secured to the nearest to the middle block and to the 50 ends of the guide rod.

60. FRANK E. WILLIAMS.
